UNITED STATES PATENT OFFICE

90,547

DESIGN FOR AN AUTOMOBILE TRUCK BODY

Nick Papas, Corona, N. Y., assignor to Alpine
Ice Cream Co. Inc., a Corporation of New York

Application May 13, 1933. Serial No. 48,114

Term of patent 14 years

To all whom it may concern:

Be it known that I, NICK PAPAS, a citizen of the Republic of Greece, residing in Corona, Long Island, in the county of Queens and State of New York, have invented a new, original, and ornamental Design for an Automobile Truck Body, of which the following is a specification, reference being had to the accompanying drawing, forming part thereof, in which:

The figure is a perspective view of the automobile truck body, showing my new design.

The opposite side of the design is substantially the same as the side shown in the drawing.

I claim:

The ornamental design for an automobile truck body, as shown and described.

Signed at the city of Washington, in the District of Columbia, this 11th day of May, 1933.

NICK PAPAS.
